Letters Patent

The Schedule referred to in these Letters Patent, and making part of the same, containing a description in the words of the said Eliphazell Nott, himself, of his Improvement for covering the smell from book stores, and improving the quality and flavor of articles cooked therein.

The specification of improvements made for equalizing the heat in, and correcting the smell from bookstoves, and for improving the quality & flavor of articles cooked thereby, especially when anthracite coal is the fuel in use. Whereas in bookstoves, having books constructed of iron plates, through which the heat is transmitted from the flame in piping along and around the same, the heat is variable, the smell offensive, and the quality and flavor of the articles cooked, injured. Therefore an improvement has been introduced, which consists in substituting stones, the heat of which, so far as the same is exposed to the action of the interior furnace or flue, but especially the furnace, is constructed in whole or in part, of brick, stone, or other material, that is a poor conductor, and so far as the same is exposed to the action of the exterior air, is constructed of tin, polished brass, or other material that is a good reflector, and also in so doing an aperture for the escape of steam to the flue in stones heated laterally. The form and relative position of which furnace flue, & stones, may be varied at pleasure, provided only the whole be so combined that the heat from the furnace and flue be transmitted to the stones through brick or stone &c, on the inside, and reflected from tin, polished brass, &c, on the outside. For

For further information reference may be had to the specifications and drawings connected herewith.

Summary.

The invention and improvement herein contemplated, consist in equalizing the heat, conserving the heat, and improving the quality & flavor of articles cooked in stoves, by so constructing and combining the furnace, flue, & oven, that the heat shall be transmitted from the former to the latter, through brick or stone, &c., on the inner side, and reflected from the polished brass, or other reflector, on the outer side, in place of being as heretofore transmitted through and reflected from iron. I therefore claim as my invention & improvement, the construction and combination of the furnace, flue and oven, whether fixed or moveable, in a cook stove, especially where anthracite coal is the fuel in use, in the manner, and for the purposes set forth, together with the uses to which the same has been or may hereafter be applied.
